LUBRICANT

Alfred L. Bayes, Kenmore, N. Y., assignor to
Carbide and Carbon Chemicals Corporation, a
corporation of New York

No Drawing. Application December 26, 1942,
Serial No. 470,213

21 Claims. (Cl. 252—47)

The invention relates to lubricants, and particularly to mineral oil lubricants having incorporated therein minor quantities of additive material adapted to improve lubrication properties, and to inhibit or retard corrosion and deterioration of the oil in normal lubrication service.

Commercial petroleum lubricating oils, as originally extracted and refined, may have certain corrosiveness toward metals. This is particularly true of those oils which are refined by a solvent extraction process. Oils which are not initially corrosive may become so under conditions of use in an internal combustion engine, where oxidation, under high temperature and pressure, usually effects certain break-down in the oil, which promotes or creates corrosive conditions, as well as other deteriorating influences. In modern automotive engines the bearing metals often are cadmium-silver, cadmium-nickel or copper-lead alloys, and these alloys are especially susceptible to corrosion in contact with mineral lubricating oils. The problem of inhibiting the corrosive action of oils on metal surfaces, and of retarding deterioration of the oil through oxidation, are, therefore, of essential importance, and while considerable thought and effort has been given to these problems in the prior art, further improvement is desirable.

In accordance with my invention there is provided new oil additive materials, adapted in very small concentrations to impart to a mineral oil, and maintain therein, substantially non-corrosive characteristics toward common bearing metals, and at the same time produce in the oil a greater resistance to deterioration through oxidation.

The additives proposed for this purpose are dimorpholine polysulfides of the characteristic structure:

in which x represents two or more sulfur atoms. Individual compounds of this structure, like dimorpholine disulfide, or products comprising mixtures of these polysulfides, including the tri-sulfide, tetrasulfide, or higher derivatives, are included within the broader scope of the invention.

Dimorpholine disulfide, of the formula:

can be prepared by the interaction of sulfur monochloride with morpholine in an inert solvent like toluene. The purified compound is a white crystalline solid containing 27.1% sulfur, and having a melting point of about 123° C. A prod-

uct comprising mixtures of these polysulfides can be made by reacting the morpholine with elemental sulfur in the presence of lead oxide or other metal oxide catalyst. By modification in the mol proportions of the reactants used, in the quantity and purity of the catalyst, or in the temperature of the reaction, products of different sulfur content can be obtained, with the sulfur varying, for example, within the range of about 32% to 42%. The melting point of these compound mixtures is not sharply defined, although the products usually melt within the range of 75% C. to 85% C., with the melting temperature decreasing as the sulfur content increases. Also with increase in sulfur content, the recovered solid products vary from white to yellow in color.

As already indicated, these new additives in oil solution exert both an anti-oxidant and a corrosion inhibiting action. It appears, however, that to obtain the optimum in each of these functions, the additive product should have a sulfur content intermediate in the range above specified, since low sulfur is better for corrosion protection, while a high sulfur content improves engine cleanliness. Polysulfide mixtures with a sulfur content of from about 32% to 39% are thus preferred for their over-all inhibitor action. These products can be obtained directly by the litharge method as described, or they can be made by mixing a low sulfur compound, like the disulfide, with products of higher sulfur content. By another alternative an auxiliary inhibitor, for either oxidation or corrosion as desired, might be used along with dimorpholine polysulfides.

The most effective concentrations of the additives will vary with different lubricating oils, and with different lubrication conditions, but for most purposes amounts within the range of 0.10% to 5.0% by weight will be found satisfactory. For greater permanency in the inhibitor action a minimum of about 0.5% is preferred, and without the aid of solubilizers, about 2.0% of the additive is all that can be dissolved in most mineral lubricating oils. Higher concentrations may, however, be desirable in special applications, such as in extreme pressure lubrication, and these contemplated in the broader scope of the invention, provided the additive can be made soluble in the oil by means of solubilizing agents.

Test results on dimorpholine polysulfide mixtures, and the pure compound dimorpholine disulfide, are shown in the following tables. Table 1 indicates the corrosion inhibiting action of the additives on bearing metals, as determined in an Underwood test apparatus, with a test run of 10 hours at 325° F.; and in Tables 2 and 3 comparative figures are listed which represent the changes in oil properties effected in inhibited and

uninhibited oil after both a 54 hour Lauson engine test and a 36 hour run in a Chevrolet engine. The oil used in the tests of Tables 1 and 2 was a Pennsylvania solvent extracted oil, of viscosity S. A. E. 10, and the Chevrolet engine test was made with a mid-continent solvent extracted oil of viscosity S. A. E. 20.

TABLE 1

Additive used	Sulfur content	Per cent weight loss of bearings		
		Cu-Pb	Cd-Ni	Ag-Cd
None		0.80	4.5	4.5
0.5% dimorpholine polysulfide	38.9	0.015	0.002	
1.0% dimorpholine polysulfide	38.9	(1)		(1)
1.0% dimorpholine disulfide	27.1	0.08		0.095

¹ No loss.

TABLE 2
54-hour Lauson engine test

Additive used	Sulfur content	Increase in—		
		Vis. at 100° F.	Per cent carbon	Neut. No. Mg.KOH/gm.
None		Per cent 35.0	0.87	1.42
0.5% dimorpholine polysulfide	38.9	3.6	0.26	0.34
1.0% dimorpholine polysulfide	38.9	3.3	0.06	0.27
1.0% dimorpholine disulfide	27.1	19.8	1.19	0.95

TABLE 3
36-hour Chevrolet engine test

Additive used	Sulfur content	Increase in—				
		Vis. at 100° F.	Per cent carbon	Neut. No. Mg.KOH/gm.	N. I. ¹	C. S. ²
None		Per cent 262	3.01		6.20	225
0.5% dimorpholine polysulfide	37.7	9.9	0.88		0.27	31
0.5% dimorpholine disulfide	27.1	19.8	0.97		0.43	15

¹ N. I.—Naphtha insolubles.

² C. S.—Chloroform solubles.

The Underwood test is well known to oil investigators, and represents severe corrosion and oxidation inducing conditions. Oxidation catalysts are sometimes used to further accelerate this test, and here also the tests were conducted in the presence of an iron naphthenate catalyst in amount equivalent to 0.01% ferric oxide. The bearing compositions are the same as those now commonly used in internal combustion engines. The values for viscosity, Conradson carbon residue, and other properties indicated, were all de-

tioned additives which may be formulated from the two components described, and the invention includes all modifications in which dimorpholine polysulfides of the structure specified constitute an essential corrosion and oxidation inhibitor, whether used alone or with other additive ingredients. The claims should also be interpreted in accordance with the disclosure given, and are intended to cover, within the broad reference to dimorpholine polysulfides, a reaction product which is a substantially pure compound, like dimorpholine disulfide, or those products which constitute mixtures of the disulfide with trisulfide, tetrasulfide or higher sulfur derivatives.

I claim:

1. A lubricant comprising a mineral oil containing corrosion and oxidation inhibiting amounts of an oil-soluble dimorpholine polysulfide of the structure:

wherein x is at least two.

2. A lubricant comprising a mineral oil containing corrosion and oxidation inhibiting amounts of an oil-soluble dimorpholine polysulfide of the structure:

wherein x is at least two and represents a sulfur content of from about 27% to 42%.

3. A lubricant comprising a petroleum lubricating oil containing corrosion and oxidation inhibiting amounts of a mixture of dimorpholine polysulfides of the structure:

wherein x is at least two.

4. A lubricant comprising a petroleum lubricating oil containing corrosion and oxidation inhibiting amounts of a mixture of dimorpholine polysulfides of the structure:

wherein x is at least two, said mixture being the product of the reaction of elemental sulfur with morpholine in the presence of a lead oxide catalyst.

5. A lubricant comprising a petroleum lubricating oil containing corrosion and oxidation inhibiting amounts of a mixture of dimorpholine polysulfides of the structure:

wherein x is at least two, representing a sulfur content of from about 32% to 42%.

6. A lubricant comprising a petroleum lubricating oil containing corrosion and oxidation inhibiting amounts of dimorpholine disulfide, said compound having the structural formula:

7. A lubricant comprising a petroleum lubricating oil containing corrosion and oxidation inhibiting amounts of dimorpholine disulfide, said compound having the structural formula:

and being the product of the reaction in an inert solvent of sulfur monochloride with morpholine.

8. A lubricant comprising a mineral oil containing corrosion and oxidation inhibiting amounts of a mixture of oil-soluble dimorpholine polysulfides of the structure:

wherein x is at least two; and an oil-soluble metal derivative of an acetoacetic ester.

9. A lubricant comprising a petroleum lubricating oil containing an additive mixture composed of corrosion and oxidation inhibiting amounts of an oil-soluble dimorpholine polysulfide of the structure:

wherein x is at least two; and detergency amounts of calcium methyl amyl acetoacetate.

10. A lubricant comprising a petroleum lubricating oil containing an additive mixture composed of corrosion and oxidation inhibiting amounts of an oil-soluble dimorpholine polysulfide of the structure:

wherein x is at least two; and detergency amounts of cobalt methyl amyl acetoacetate.

11. A lubricant comprising a petroleum lubricating oil containing an additive mixture composed of corrosion and oxidation inhibiting amounts of an oil-soluble dimorpholine polysulfide of the structure:

wherein x is at least two; and detergency amounts of chromium methyl amyl acetoacetate.

12. A lubricant comprising a petroleum lubricating oil containing an additive mixture composed of about 0.2% to 1.0% of a mixture of dimorpholine polysulfides of the structure:

wherein x is at least two; and about 0.2% to 1.0% of a metal derivative of methyl amyl acetoacetate.

13. A lubricant comprising a petroleum lubricating oil containing an additive mixture composed of about 0.2% to 1.0% of a mixture of dimorpholine polysulfides of the structure:

wherein x is at least two and represents a sulfur

content of from about 32% to 42%; and about 0.2% to 1.0% of calcium methyl amyl acetoacetate.

14. A lubricant comprising a petroleum lubricating oil containing an additive mixture composed of about 0.2% to 1.0% of dimorpholine disulfide, said compound having the structural formula:

and about 0.2% to 1.0% of a metal derivative of methyl amyl acetoacetate.

15. Method of lubricating bearing surfaces composed of metal having the corrosion susceptibility of copper-lead and cadmium-silver alloys, which comprises applying to the bearing surfaces a lubricant having incorporated therein, in corrosion-inhibiting amounts, a dimorpholine polysulfide of the structure:

wherein x is at least two.

16. Method of lubricating bearing surfaces composed of metal having the corrosion susceptibility of copper-lead and cadmium-silver alloys, which comprises applying to the bearing surfaces a lubricant having incorporated therein, in corrosion-inhibiting amounts, a mixture of dimorpholine polysulfides of the structure:

wherein x is at least 2, and represents a sulfur content of from about 32% to 42%.

17. Method of lubricating bearing surfaces composed of metal having the corrosion susceptibility of copper-lead and cadmium-silver alloys, which comprises applying to the bearing surfaces a lubricant having incorporated therein, in corrosion-inhibiting amounts, dimorpholine disulfide of the structural formula:

18. Method of lubricating bearing surfaces composed of metal having the corrosion susceptibility of copper-lead and cadmium-silver alloys, which comprises applying to the bearing surfaces a lubricant having incorporated therein minor

amounts of an additive mixture composed of an oil-soluble dimorpholine polysulfide of the structure:

wherein x is at least two; and an oil-soluble metal derivative of an acetoacetic ester.

19. Method of lubricating bearing surfaces composed of metal having the corrosion susceptibility of copper-lead and cadmium-silver alloys, which comprises applying to the bearing surfaces a lubricant having incorporated therein an additive mixture composed of about 0.2% to 1.0% of a mixture of dimorpholine polysulfides of the structural formula:

wherein x is at least two; and about 0.2% to 1.0% of a metal derivative of methyl amyl acetoacetate.

20. Method of lubricating bearing surfaces composed of metal having the corrosion susceptibility of copper-lead and cadmium-silver alloys, which comprises applying to the bearing surfaces a lubricant having incorporated therein minor amounts of an additive mixture composed of about 0.2% to 1.0% of dimorpholine disulfide, said compound having the structural formula:

and about 0.2% to 1.0% of a metal derivative of methyl amyl acetoacetate.

21. Method of lubricating bearing surfaces composed of metal having the corrosion susceptibility of copper-lead and cadmium-silver alloys, which comprises applying to the bearing surfaces a lubricant having incorporated therein minor amounts of an additive mixture composed of about 0.2% to 1.0% of a mixture of dimorpholine polysulfides of the structural formula:

wherein x is at least two and represents a sulfur content of from about 32% to 42%; and about 0.2% to 1.0% of calcium methyl amyl acetoacetate.

ALFRED L. BAYES.

CERTIFICATE OF CORRECTION.

Patent No. 2,351,657.

June 20, 1944.

ALFRED L. BAYES.

It is hereby certified that error appears in the printed specification of the above numbered patent requiring correction as follows: Page 1, second column, line 13, for "75% C. to 85% C." read --75° C. to 85° C.--; line 48, after the word "these" insert --are--; page 2, second column, line 1, for "present" read --per cent--; and that the said Letters Patent should be read with this correction therein that the same may conform to the record of the case in the Patent Office.

Signed and sealed this 8th day of August, A. D. 1944.

(Seal)

Leslie Frazer
Acting Commissioner of Patents.
